UNITED STATES PATENT OFFICE.

THOMAS BENNINGFIELD, OF COATS, KANSAS, ASSIGNOR OF ONE-THIRD TO ALFRED LANCASTER, OF ALVA, OKLAHOMA.

SIGNAL.

Application filed January 2, 1923 Serial No. 610,262.

To all whom it may concern:

Be it known that I, THOMAS BENNINGFIELD, a citizen of the United States, residing at Coats, in the county of Pratt and State of Kansas, have invented new and useful Improvements in Signals, of which the following is a specification.

This invention relates to improvements in road signals and has for an object the provision of means designed to be positioned within a roadway in advance of a danger point operated by approaching vehicles, whereby a signal will be operated to warn the drivers of vehicles approaching from another direction.

Another object of the invention is the provision of a signal operated means, which will be rendered active by vehicles approaching a danger point and the parts returned to normal position after such point has been passed, the construction and arrangement being such that vehicles traveling in an opposite direction will not effect the operation of the signal.

With the above and other objects in view, the invention further includes the following novel features and details of construction, to be hereinafter more fully described, illustrated in the accompanying drawings and pointed out in the appended claims.

In the drawings:—

Figure 1 is a section taken longitudinally of a roadway and showing the signal in danger position.

Figure 2 is a section taken transversely of the roadway and along the longitudinal center of the setting trip.

Figure 3 is a similar view taken longitudinally of the release trip.

Figure 4 is a top plan view.

Figure 5 is an enlarged elevation partly broken away showing the upper end of the signal standard with the semaphore in danger position.

Figure 6 is an elevation of the upper end of the standard with the semaphore in danger position, but illustrating a different arrangement of signal lamp.

Referring in detail to the drawings, wherein like characters of reference denote corresponding parts, the signal which is designed to be positioned at one side of a roadway adjacent a point of danger, comprises a standard 10. This standard has secured at its upper end, spaced arms or

plates 11 which are horizontally arranged and which have pivotally mounted between their outer ends as shown at 11^a, a signal arm or semaphore 12. This arm or semaphore is normally arranged in vertical position and when in such position indicates clear or safety, but is adapted to be moved to a horizontal position to indicate danger.

For the purpose of moving the arm to danger position, there is provided a setting trip which is indicated generally at 13 and which is disposed transversely of the roadway in advance of the danger point, so that the setting trip will be operated to set the signal arm at danger before the vehicle reaches the danger point.

This setting trip comprises a plate 14 which is arranged within a trough 15, the upper edge of the latter being substantially flush with the surface of the roadway. The trough is formed of suitable material and may be of any suitable shape and is provided in its top with a longitudinally disposed slot 16 for the passage of the plate 14. This plate is normally vertically disposed and is provided along its lower edge with a fulcrum bar 17, from which extends an arm 18, the latter projecting above the roadway. The fulcrum bar 17 extends beyond the ends of the plate 14 to provide trunnions 19 and

the latter are mounted in suitable bearings provided in abutments 20 at each end of the trough 15. The plate is yieldingly held in centered position by means of a plurality of springs 21, which extend from the plate to the opposite sides of the trough. Also extending from the opposite sides of the plate 14 are transversely curved plates or shields 22 which are arranged beneath the slot 16 and act to maintain the slot in closed condition when the plate is pivotally moved in either direction by the passage of a vehicle thereover.

The inner end of the signal arm 12 has secured thereto one end of a flexible member or cable 23 which passes over a pulley 24 mounted between the plates 11 and downward around a pulley 25 carried by the standard 10. The flexible member or cable may then be passed through a pipe or conduit 26 extending along the side of the roadway and suitably supported upon standards 27. The flexible member or cable 23 then passes around spaced pulleys 28 which are carried by a standard 29 and its opposite

100
105
110

end is connected to the arm 18. An extensible section or spring 30 is included in the flexible member or cable 23 to prevent undue strain.

- 5 Pivots mounted between the plates 11 as shown at 31 is a latch 32, one end of which is provided with a beveled headed hook 33 which is adapted to engage the inner end of the arm 12 when the latter is 10 elevated to a danger position so as to maintain the arm in such position until purposely released. The opposite end of the latch 32 is forced outwardly by means of a spring 34 to yieldingly hold the hook in 15 engagement with the signal arm. Located transversely of the roadway and spaced from the trough 15 is a trough 35 and mounted within this trough is a release trip 36 which is capable of vertical movement. 20 This trip is transversely beveled in opposite directions as shown and is normally maintained slightly above the surface of the roadway by means of a plurality of springs 37, the latter bearing against the under face 25 of the trip and upon a shoulder or ledge 38 provided in abutments 39 at opposite ends of the trough 35. Upward movement of the trip 36 is limited by stop yokes 40 located at each end of the trough 35. 30 One end of the trip 36 is connected to the lower end of the latch 32 by means of a cable 41, the said cable passing over a pulley 42 carried by the standard 10. In addition, the standard is connected to the signal arm 12 35 by means of a spring 43 which acts to draw the said arm downward when the latch 32 is released.

Extending outwardly from the upper end of the standard 10 is an arm 44 which carries at its outer end an audible signal in the form of a plate or gong 45. This signal is located in the path of the outer end of the signal arm 42 and the latter is provided at said outer end with a metallic member or 45 striker 46.

Normally, the signal arm 12 is arranged in lowered or safety position and a vehicle approaching a point of danger protected by the signal will strike the upper edge of the 50 plate 14 and move said plate in the direction of the arrow shown in Figures 1 and 4. The plate 14 will then be moved pivotally in the direction of said arrow, whereupon the cable 23 will move the signal arm 12 pivotally to a 55 raised position, which arm during its upward movement will strike the signal or gong 45 so as to produce an audible signal. The inner end of the signal arm 12 will be engaged beneath the head of the latch 32 so that the said arm will be held in danger 60 position until the vehicle reaches the trip 36. This trip will then be depressed so as to exert a pull upon the cable 31 and move the head of the latch outward to release the arm 12 and the latter will fall by gravity assist-

ed by the spring 43 to its normal or inactive position. It will be apparent that a vehicle travelling in a direction opposite the arrow will move the trip plate 14 in its direction of travel so that no pull will be exerted upon the cable 23 and therefore no action of the signal will occur.

In addition to the audible signal 45, there is provided a visual signal in the form of an electric bulb 47 which is located within an opening provided in the signal arm or semaphore 12, a colored lens being preferably provided upon opposite sides of the bulb and closing the opening. The bulb 47 is connected by means of a conductor 48 to a contact plate 49 which is carried by the inner end of the arm 12 and which is engaged by the latch 32. This latch is in electrical connection with a suitable source of current by means of a conductor 50, while the bulb may be grounded in any suitable manner. When the signal arm or semaphore 12 is elevated and engages the latch 32, a circuit will be completed through the bulb 47.

The arrangement shown in Figure 6 of the drawings differs only in regard to the position and arrangement of the signal lamp 51. This lamp is mounted upon the outer end of the arm 44 which carries the audible signal or gong 45 and current is supplied to the lamp 51 by a cable 52 which connects the lamp with the plate or contact 49, as in the previously described form of the invention. By mounting the lamp 51 upon the arm 44 the said lamp will not be subjected to danger of injury due to the movements of the semaphore 12.

The invention is susceptible of various changes in its form, proportions and minor details of construction and the right is herein reserved to make such changes as properly fall within the scope of the appended claims.

Having described the invention what is claimed is:—

1. In a road signal, a standard, a normally inactive signal arm pivotally mounted thereon, a vehicle operated member, means operatively connecting said member with the signal, whereby the latter will be moved to an active position when the member is actuated, an audible signalling device located in the path of the signal arm and actuated thereby when the latter is moved to an active position, means for holding the arm in signalling position and means spaced from the vehicle operated member and also actuated by the vehicle, whereby the holding means will be operated to release the arm.

2. In a road signal, a standard, a normally inactive combined signal arm and striker pivotally mounted thereon, a gong located in the path of said arm, a vehicle operated member, means operatively connecting said member with the signal, where-

by the latter will be moved to an active position when the member is actuated, means for holding the arm in signalling position and means spaced from the vehicle operated member and also actuated by a vehicle, whereby the holding means will be operated to release the arm.

3. In a road signal, a standard, a normally inactive signal arm pivotally mounted thereon, a pivotally mounted vertically disposed horizontal plate arranged transversely of the roadway in the path of vehicle travel, yieldable means for holding the plate in normal position, means operatively connecting the plate with the signal, whereby the latter will be moved to an active position by vehicles travelling in one direction only, means for holding the arm in signalling position and means spaced from the plate and

located in the path of vehicular travel, whereby the holding means will be actuated to release the arm.

4. In a road signal, a standard, a normally inactive signal arm pivotally mounted thereon, a vehicle operated member, means operatively connecting said member with the signal, whereby the latter will be moved to an active position when the member is actuated, a pivotally mounted spring pressed latch located upon the standard and engaging the arm to hold the latter in signalling position and means spaced from the vehicle operated member in the path of vehicular travel and operatively connected to the latch, whereby the latter will be actuated to release the arm.

In testimony whereof I affix my signature.
THOMAS BENNINGFIELD.
